UNITED STATES PATENT OFFICE.

HOLDEN RIGBY, OF PATERSON, NEW JERSEY.

LINGO.

SPECIFICATION forming part of Letters Patent No. 591,496, dated October 12, 1897.

Application filed May 18, 1897. Serial No. 637,095. (No model.)

To all whom it may concern.

Be it known that I, HOLDEN RIGBY, a citizen of the United States, residing in Paterson, county of Passaic, and State of New Jersey, 5 have invented certain new and useful Improvements in Lingoes; and I do hereby declare the following to be a full, clear, and exact description of the invention, such as will enable others skilled in the art to which it app pertains to make and use the same, reference being had to the accompanying drawings, and to letters of reference marked thereon, which form a part of this specification.

This invention relates to improvements in 15 lingoes or heddle-weights for Jacquard looms; and its object is to provide a lingo which can be cheaply and easily manufactured and which permits a ready and quick connection with the tail-cord and the sure retention of 20 the same.

The invention consists in the improved heddle-weight or lingo, substantially as will be hereinafter more fully described, and finally embodied in the clauses of the claim.

25 Referring to the accompanying drawings, in which like letters of reference indicate corresponding parts in each of the several views, Figure 1 is a side elevation of my improved lingo and of a portion of a tail-cord connected therewith; Fig. 2, a front elevation of Fig. 1; Fig. 3, an enlarged transverse section through the upper portion of Fig. 1; Fig. 4, a front elevation of the lingo with the head flattened out; and Figs. 5 and 6, respectively, 30 sectional views on the lines x x and x' x' of Fig. 2.

In said drawings, a is the body of the lingo, the upper portion of which is flattened out, as at a' and a'' , and the ears or flaps a^3 a^3 thus 35 produced are bent to form a channel a^4 .

It must be remarked that the channel a^4 is

conical-shaped, which shape is produced or obtained by diminishing the thickness of the head in its central portion a' and leaving the top portion a^2 thicker than said central portion. This is very important, as by this arrangement not only a seat for the knot b' of the tail-cord b is formed within the conical channel a^4 , but the wall constituting said channel is greatly strengthened, the thicker 45 portion a^2 on one side and the body a on the other side strengthening and protecting the thin portion a' , and thus preventing its splitting.

The above will be better understood when 55 it is taken into consideration that the lingoes or heddle-weights are generally formed out of hard (inflexible, brittle) wire.

As the flaps a^3 a^3 do not come in close contact with each other, a slot is formed between 60 them of a size sufficient to permit the quick and ready connecting with the tail-cord, as will be manifest.

Having thus described my invention, what I claim as new, and desire to secure by Letters Patent, is—

A lingo or heddle-weight consisting of a body having means for connecting a tail-cord thereto, said means consisting of side flaps bent toward each other, the metal at the top 70 between the flaps being thicker than the lower portion thereof to thereby form a conical seat for the tail-cord and a reinforce for the head of the lingo, substantially as described.

In testimony that I claim the foregoing I 75 have hereunto set my hand this 11th day of May, 1897.

HOLDEN RIGBY.
